UNITED STATES PATENT OFFICE.

CHARLES EDWIN PATTERSON, OF SAN FRANCISCO, CALIFORNIA.

ELECTRICALLY-CONTROLLED HEATER.

1,418,671.

Specification of Letters Patent. Patented June 6, 1922.

Application filed November 17, 1920. Serial No. 424,642.

To all whom it may concern:

Be it known that I, CHARLES E. PATTERSON, a citizen of the United States, and a resident of San Francisco, in the county of 5 San Francisco and State of California, have invented certain new and useful Improvements in Electrically-Controlled Heaters, of which the following is a specification.

My invention is an improvement in electrically controlled heaters, and has for its 10 object to provide a heater of the character specified, wherein the heating element is so supported and mounted that the radiated heat rays may be reflected either directly 15 forward, or in the form of a cone, and wherein means is provided in connection with the support for insuring a free and unrestricted flow of air about the heater.

In the drawings: 20 Figure 1 is a side view of the improved heater,

Figure 2 is a vertical section through the heater proper,

Figure 3 is a front view, 25 Figure 4 is an enlarged detail section through the casing and reflector,

Figure 5 is an enlarged detail at the rim of the casing,

Figure 6 is a section on the line 6—6 of 30 Figure 2,

Figure 7 is a detail section at the adjusting screw.

In the present embodiment of the invention, the improved heater comprises a bowl-shaped casing or shell 1, which is provided 35 at its periphery with a flattened portion 2, that is, with a ring which is co-axial with the axis of the shell, the body of the shell being the segment of a sphere. At the center of the shell there is secured a lug 3, the 40 said lug having laterally extending flanges 4 which are riveted to the shell, and means is provided in connection with the lug for permitting the shell to be connected to a 45 standard to be described.

The free edge of the ring portion 2 of the shell is beaded as shown at 5, and upon this portion there is mounted to move a deflecting ring 6, the said ring having its rear or 50 inner edge beaded as shown at 7 to engage the bead 5, to limit the outward movement of the ring 6 with respect to the portion 2 of the shell. The forward edge of the ring 6 is also beaded, as shown.

55 Within the shell 1 there is arranged a conical support 8, and this support has its

free edge lapped upon the bead 5 of the portion 2 of the shell. As shown more particularly in Figure 5, the free edge of the support 8 is curved to fit the bead, and 60 bolts and nuts indicated at 9 are provided for connecting the said free edge to the bead, the bolts being passed through the lapped portions of the shell and the support.

The heater comprises a hollow frusto-conical body 10 having its small end connected to the center of the support 8, by means of the mechanism shown in Figure 2. The said mechanism comprises a socket 11 which has a stem passed through the center of the 70 support 8 and engaged by a nut 12 and a screw 13 which is passed through the small end of the element 10 and has threaded engagement with the socket.

A resistance wire 14 is passed spirally 75 about the element 10, extending from the large end to the small end, and the terminals of the wire are connected with contact buttons 15 on an insulated block 16 which is bolted to the support 8, as indicated at 17. With the contact buttons 15 the wires of a conducting cable 18 are connected, the said wires passing through an insulated sleeve 19 in the shell.

The heating element 10 is braced against 80 the support 8, by means of rods 20. Each of these rods has one end reduced and passed through the support, and headed on the rear face thereof. The forward end of each of the rods is beveled to fit against the peripheral surface of the heating element. As 85 shown in Figure 3, three of the rods are provided, the said rods being spaced at angular intervals of 120°.

Between the heating element and the support 8 there is arranged a frusto-conical reflector indicated at 21. The said reflector is connected to the support 8 at intervals by means of rivets 22. These rivets are of a length such that a spacing sleeve 23 may be 90 arranged on each rivet between the reflector and the support, and the reflector is thus held in spaced relation with respect to the support.

Between the rivets 22 the reflector is corrugated as shown at 21^a, the corrugations being of considerable depth as shown, and each corrugation gradually increases in cross sectional area from the closed end of the reflector indicated at 24 to the open end.

105 In the present instance, six rivets 22 are provided, the said rivets supporting the re-

- reflector in spaced relation with respect to the support 8, and with respect to the heating element 10. Thus when the heating element is heated, air may flow inwardly between the support 8 and the reflector and outwardly between the heating element and the reflector or in the opposite direction, the heated air passing outwardly and the cold air passing inwardly to be heated.
- 5 When the ring 6 is in the position of Figure 2, the heat rays will be reflected outwardly in a conical formation. When however, the ring 6 is pushed outwardly until the bead 7 engages the bead 5, the heat rays will be reflected in a cylindrical formation directly forward. A fender and guard 25 of perforate material, as for instance woven wire, is arranged at the open end of the shell, the said guard being the segment of 15 a sphere of greater radius than the radius of the shell.
- 10 The shell is connected to a suitable stand by means of the lug 3. In Figure 1 there is shown a stand consisting of upper and lower 20 telescoping sections 26 and 27, the latter sections having a suitable base 28.
- 15 The section 27 is hollow, and the section 26 slides in the section 27, and is held in 25 adjusted position by means of a set screw 29 which is threaded through the section 27. The lug 3 laps upon the flattened upper end of the section 26, and a set screw 30 is threaded through the lug and through the flattened portion of the section to clamp the 30 parts together.
- 35 I claim:
1. An electrically controlled heater, comprising a bowl-shaped shell having at its free edge a marginal ring, a heater and reflector supported within the shell and a deflecting ring mounted to slide on the marginal ring of the shell, to move beyond the free edge of the marginal ring or back into register with said ring, said heater comprising a frusto-conical hollow shell arranged with its large end outward and carrying a heating element, a conical support for supporting the heater and reflector within the shell and arranged with its large end outward and having said large end secured to the marginal ring of the shell, the reflector being arranged between the support and the heater shell and spaced apart from both, with its large end outward and carrying a heating element, a conical support for supporting the heater and reflector within the shell and arranged with its large end outward and having said large end secured to the marginal ring of the shell, the reflector being arranged between the support and the heater shell and spaced apart from both, said reflector being corrugated.
  2. An electrically controlled heater comprising a bowl-shaped shell having at its free edge a marginal ring, a heater and reflector supported within the shell and a deflecting ring mounted to slide on the marginal ring of the shell, to move beyond the free edge of the marginal ring or back into register with said ring, said heater comprising a frusto-conical hollow shell arranged with its large end outward and carrying a heating element, a conical support for supporting the heater and reflector within the shell and arranged with its large end outward and having said large end secured to the marginal ring of the shell, the reflector being arranged between the support and the heater shell and spaced apart from both, said reflector being corrugated, and the depth and width of the corrugations gradually increasing from within outward.
  3. An electrically controlled heater comprising a bowl-shaped shell having at its free edge a marginal ring, a heater and reflector supported within the shell and a deflecting ring mounted to slide on the marginal ring of the shell, to move beyond the free edge of the marginal ring or back into register with said ring, said heater comprising a frusto-conical hollow shell arranged with its large end outward and carrying a heating element, a conical support for supporting the heater and reflector within the shell and arranged with its large end outward and having said large end secured to the marginal ring of the shell, the reflector being arranged between the support and the heater shell and spaced apart from both, said reflector being corrugated.
  4. An electrically controlled heater, comprising a bowl-shaped shell having at its free edge a marginal ring, a heater and reflector supported within the shell and a deflecting ring mounted to slide on the marginal ring of the shell, to move beyond the free edge of the marginal ring or back into register with said ring, said heater comprising a frusto-conical hollow shell arranged with its large end outward and carrying a heating element, a conical support for supporting the heater and reflector within the shell and arranged with its large end outward and having said large end secured to the marginal ring of the shell, the reflector being arranged between the support and the heater shell and spaced apart from both, said reflector being corrugated.
  5. An electrically controlled heater, comprising a bowl-shaped shell having at its free edge a marginal ring, a heater and reflector supported within the shell and a deflecting ring mounted to slide on the marginal ring of the shell, to move beyond the free edge of the marginal ring or back into register with said ring, said heater comprising a frusto-conical hollow shell arranged with its large end outward and carrying a heating element, the reflector being spaced apart from the first named shell and from the heating shell.
  6. An electrically controlled heater, comprising a bowl-shaped shell having at its free edge a marginal ring, a heater and reflector supported within the shell and a deflecting ring mounted to slide on the marginal ring of the shell, to move beyond the free edge of the marginal ring or back into register with said ring, said heater comprising a frusto-conical shell arranged with its large end outward and having a heating element, the reflector encircling the heater shell and being spaced apart therefrom.
  7. An electric heater comprising a casing, a reflector within the casing, a heating element within the reflector, said reflector being of conical form to direct the rays emanating from the element conically from the heater,

and a ring carried upon the peripheral edge of the casing and movable inwardly and outwardly to occupy a position wherein the rays passing from the reflector are directed 5 forward in the form of a cylinder.

8. An electric heater comprising a frusto-conical reflector having corrugations formed therein which gradually increase in cross sectional area from the closed end of the reflector to the open end thereof, a frusto-conical body supported concentrically within the reflector, and a heating element coiled about the body.

9. An electric heater comprising a conical support, a reflector of frusto-conical form arranged concentrically of the support and in spaced relation thereto to allow the circulation of air between the support and reflector, a frusto-conical body arranged concentrically within the reflector, and a heating element coiled about the body.

10. An electric heater comprising a conical support, a conical reflector substantially concentrically with the support and arranged in 25 spaced relation thereto to permit of the circulation of air between the two, said reflector being corrugated radially with each corrugation gradually increasing in cross sectional area from the closed end to the open end of the reflector, and a heating element within 30 the reflector.

11. An electric heater comprising a conical support, a conical reflector substantially concentrically with the support and arranged in 35 spaced relation thereto to permit of the cir-

culation of air between the two, said reflector being corrugated radially with each corrugation gradually increasing in cross sectional area from the closed end to the open end of the reflector, and a heating element arranged in the form of a cone and concentrically within the reflector. 40

12. An electric heater comprising a conical support, a conical reflector substantially concentrically with the support and arranged in 45 spaced relation thereto to permit of the circulation of air between the two, said reflector being corrugated radially with each corrugation gradually increasing in cross sectional area from the closed end to the open end of 50 the reflector, a conical body arranged concentrically within the reflector, and a heating element spirally upon the body.

13. An electric heater comprising a casing, a reflector within the casing, a heating element within the reflector, said reflector being of conical form to direct the rays emanating from the element conically from the heater, and means carried by the casing movable to 55 occupy a position wherein the rays passing from the reflector are directed forwardly in the form of a cylinder.

14. A reflector for electric heaters having a conical form and formed with radially extending corrugations, each of the corrugations gradually increasing in cross sectional area from the closed end of the reflector to 60 the open end thereof.

CHARLES EDWIN PATTERSON.
